UNITED STATES PATENT OFFICE.

ALBERT H. STEBBINS, OF LOS ANGELES, CALIFORNIA.

AIR CLASSIFIER.

Application filed September 28, 1926. Serial No. 138,142.

This invention relates to air classifiers and more particularly to a tower-like construction in which the heavier particles pass downwardly through a plurality of classifying chambers for successive treatments.

In order to separate or classify fine dust-like materials through the use of air, it is necessary to subject the materials being treated repeatedly to the gentle separating action of slight air currents. Should it be attempted to effect a complete classification of fine dust-like particles by a single air treatment the strength of the air employed would either fail to completely remove the fine dust-like particles from the slightly larger particles, or it would carry off many of the larger particles with the finer particles.

The present invention therefore relates to an air classifier designed more particularly for use in the separation of fine dust-like particles and which is provided with a plurality of classifying chambers arranged one above the other so that the materials that pass through one chamber are delivered to the next for further treatment.

An important feature of the present invention resides in the construction whereby the material treating casing is divided into a plurality of chambers in each of which is provided a group of deflectors or screens arranged to disseminate the materials and to retard their downward travel within the casing so that the materials are subjected to the classifying action of gentle currents of air within each chamber.

Another feature of the invention resides in the construction whereby the deflectors or screens are arranged to direct the materials back and forth from one side of the casing to the other as they pass downwardly therein.

Still another feature of the invention resides in a classifying casing having mounted therein a plurality of groups of screens formed of individual screens each of which is provided with apertures that are large enough to permit the largest particles being treated to pass through the successive screens without lodging in the apertures.

Other features of the invention and novel combination of parts in addition to the above will be hereinafter described in connection with the accompanying drawings, which illustrate one good practical form of the invention.

In the drawings—

Fig. 1 is a vertical sectional view through an air classifier constructed in accordance with the present invention;

Fig. 2 is an edge view of Fig. 1 looking 60 towards the right-hand edge thereof; and

Fig. 3 on a slightly enlarged scale is a sectional view taken on the line 3—3 of Fig. 1.

The casing of the classifier forming the subject matter of the present invention preferably has a tower-like construction so that different classifying chambers may be formed in the casing one below the other, and the casing is preferably given more or less of a rectangular configuration in cross-section, as 65 will be apparent from Fig. 3 of the drawing, so that the width of the casing between its side walls 10 is not very great. This is desirable because the air passing up through the screens within the casing can be better 70 controlled in a narrow casing than in a wide one, as will be presently more fully pointed out.

The side walls 10 are connected by the end or edge walls 11, and the upper end of 80 the casing is closed by the cover 12, while the lower end of the casing is provided with the inclined walls 13 and 14 arranged to direct the heavier materials into the discharge spout 15, which spout may be connected to a closed bin 16. The materials to be treated may be delivered to the upper end of the tower-like casing by a feed hopper 17 and the size of the opening 18 of the feed hopper through which the materials pass into 85 the casing may be controlled by adjusting the sliding gate 19.

As stated, one of the features of the present invention resides in the construction whereby the classifier is provided with a plurality of classifying chambers disposed one below the other so that the heavier materials may pass from one chamber to the next for retreatment. The tower-like casing may be of sufficient height to have any desired number of these classifying chambers formed therein, and in the construction shown the tower is provided with three separate chambers designated as A, B and C. These chambers are conveniently formed in the casing 100 by providing the casing with an air inlet pipe or conduit 20 which extends across the casing in a downwardly inclined direction from one wall 11 thereof to a position near the opposite wall 11 so that a relatively nar- 105 110

row passage 21 is formed through which the heavier materials may flow from one chamber to the next for further treatment.

It is desirable to provide means for disseminating the materials delivered into each chamber and for retarding their progress downwardly through the chambers. This may be done by providing a baffle within each chamber and each of these baffles may 10 be constructed of a number of screens or deflectors. In the construction shown, each of the chambers A, B and C is provided with a series of screens 22 which are supported in a downwardly inclined direction as shown, and 15 the screens are positioned in close proximity to each other so that relatively narrow air passages 23 are provided between them. The upper end of each screen is secured to or is disposed in close proximity to a wall 11 20 of the casing and the opposite sides of each screen may be secured to the side walls 10 of the casing. The width of the casing from one wall 10 to the other should be relatively narrow because it is found that the 25 strength of the air currents passing upwardly through one or more narrow screens is much more uniform throughout the width of the screens than the strength of the air passing upwardly through wide screens.

30 It is important to note that these screens do not serve to grade or size the materials being treated, as in the case of the ordinary screen, but that their apertures are sufficiently large to permit the largest particles being treated within the casing to pass 35 through the various screens without lodging in the apertures to clog the same. It will therefore be seen that the materials delivered into any one of the chambers will work 40 downwardly through a number of the screens and will slide downwardly within the spaces 23 provided between these screens. In this manner the various particles are thoroughly disseminated and exposed to the action of the 45 air passing upwardly through the screens.

The means for producing rising currents of air within the different chambers may be variously constructed, and in the embodiment of the invention shown air from the 50 atmosphere or from a source of air pressure, such as a blast fan 24, is led into the chambers through apertures 25 formed in the upper face of the air conduit 20 and these apertures are preferably provided with overhanging lips 26 which prevent the materials 55 within the casing from entering the apertures 25. Each chamber A, B and C is preferably provided with an enlargement 27 formed at the edge of the casing lying opposite the delivery end of the inclined screens; this enlarged portion 27 is provided 60 to form a passage between the ends of the screens and the edge wall of the casing adjacent the same, and also to form a space 65 at one side of the casing adapted to receive

the suction pipe 28 which extends downwardly within the casing. Each bulging portion 27 is provided at its lower end with an inclined wall 29 which slopes downwardly in a direction to direct the materials into the 70 discharge passage 21 above mentioned. The suction pipe 28 is provided with a slot 30 through which air is drawn into the exhaust pipe from the casing, and it should be noted that the slot 30 is formed in that wall of the 75 pipe which faces away from the interior of the casing. This arrangement is desirable in order that the air will have to pass around the pipe 28 before entering the slot 20, thus giving the particles suspended in the air an 80 opportunity to settle before they enter the slot 30. The materials that settle about the pipe 28 will pass downwardly into the discharge pipe 31 and such materials as settle within the exhaust pipe 28 will escape 85 through a small opening 32 in the lower end of this pipe. The arrangement just described is such that air will pass upwardly through the screens 22, as will be apparent from the arrows, and will serve to carry upwardly through the screens into the upper portion of each chamber the finer particles. If desired one or more air inlet openings 33 90 may be provided in an edge wall 11 of the casing to admit air into the casing adjacent 95 the upper end of some of the screens. Each of the exhaust pipes 28 may be connected to a main pipe 34 which leads to the suction side of a fan 35.

As above indicated the air classifier forming the subject matter of the present invention is particularly well adapted to classify very fine dust-like materials, and by providing a large number of screens 22 in each chamber, the fine dust-like materials 100 working downwardly through these screens will be thoroughly subjected to the action of the gentle air currents passing up through the apertures of the screens and through the air passages 23 between the adjacent screens. 110 By arranging the classifying chambers in series one above the other so that the materials discharged from one chamber pass into the next for further treatment, the materials may be treated over and over again 115 until the desired classification is effected. It will be noted that the screens 22 in the uppermost chamber A are arranged to direct the materials across the chamber to the left-hand side thereof, whereas the 120 screens in the second chamber B serve to direct the materials in the opposite direction towards the right-hand side of the casing. In other words, the screens in the different chambers are given a zigzag arrangement so 125 that they direct the materials back and forth across the casing as they pass downwardly therein, more thoroughly to subject the materials to the action of the rising air currents.

What is claimed is:—

1. An air classifier for classifying fine, dust-like particles, comprising in combination, a tower-like casing, means for delivering the fine, dust-like materials to be treated to the upper part of the casing, means for dividing the casing into a plurality of classifying chambers arranged one above the other so that the heavier particles pass downwardly through the successive chambers, a group of deflectors mounted in each chamber to disseminate the materials and retard their downward travel there-through, and means for producing currents of air within the chambers to carry off the lighter particles. 70
2. An air classifier for classifying fine, dust-like particles, comprising in combination, a tower-like casing, means for delivering the fine, dust-like materials to be treated to the upper part of the casing, means for dividing the casing into a plurality of classifying chambers arranged one above the other so that the heavier particles pass downwardly through the successive chambers, a group of screens mounted within each chamber to retard the downward travel of the materials therein, and means for producing currents of air passing through the screens to carry off the lighter particles. 75
3. An air classifier, comprising in combination, a tower-like casing, means for delivering the materials to be treated to the upper part of the casing, means for dividing the casing into a plurality of classifying chambers arranged one above the other so that the heavier particles pass downwardly through the successive chambers, a group of screens mounted within each chamber to disseminate the materials, and means for introducing air into each chamber below the screens and for exhausting the air from each chamber at a point above the screens to carry off the lighter particles. 90
4. An air classifier, comprising in combination, a tower-like casing, means for dividing the casing into a plurality of classifying chambers arranged one above the other so that the heavier particles pass downwardly through the successive chambers, a group of deflectors mounted in each casing to disseminate the materials and retard their downward progress therein, means for introducing air into and for exhausting it from each chamber, and means for delivering the materials to be treated into the upper portion of the casing to pass downwardly therein so that the materials passing through the successive chambers are subjected to fresh air currents in each chamber. 105
5. An air classifier, comprising in combination, a tower-like casing, means for dividing the casing into a plurality of classifying chambers arranged one above the other so that the heavier particles pass down- 110
- wardly through the successive chambers, a group of screens mounted in each chamber to retard the downward progress of the materials through the casing and having apertures that are large enough to permit the largest materials being treated to pass through the successive screens without lodging in the apertures, means for delivering the materials to be treated into the upper portion of the casing, and means for producing currents of air within the chambers to carry off the lighter particles. 120
6. An air classifier for classifying fine, dust-like particles, comprising in combination, a casing, means for delivering the fine, dust-like materials to be treated into the upper part of the casing, a plurality of groups of screens mounted in the casing to direct the materials back and forth from one side of the casing to the other as they pass downwardly within the casing, each group of screens being formed of a series of screens mounted one below the other and provided with apertures that are large enough to permit the largest particles being treated to pass through the successive screens without lodging in the apertures, and means for producing currents of air within the casing to carry off the lightest particles. 125
7. An air classifier, comprising in combination, a tower-like casing, means for delivering the materials to be treated to the upper part of the casing, means for dividing the casing into a plurality of classifying chambers arranged one above the other so that the heavier particles pass downwardly through the successive chambers, a group of baffles mounted in each chamber to retard the progress of the materials downward through the chamber and arranged to provide a space above the baffles in which the particles within the air may settle, and means for passing air upwardly through the baffles. 130
8. An air classifier, comprising in combination, a tower-like casing, means for delivering the materials to be treated to the upper part of the casing, means for dividing the casing into a plurality of classifying chambers arranged one above the other so that the heavier particles pass downwardly through the successive chambers, a group of baffles mounted in each chamber to retard the progress of the materials downward through the chamber, and means for exhausting the air from each chamber comprising an exhaust pipe extending downwardly within the chamber at one side thereof and having an air inlet slot formed in the wall of the pipe that faces away from the central portion of the casing. 135
9. An air classifier for classifying fine, dust-like particles, comprising in combination, a casing, means for delivering the fine- 140

- dust-like materials to be treated into the upper portion of the casing to pass downwardly therein, a series of inclined screens mounted in the casing one above the other 5 in close proximity to each other to retard the downward passage of the materials within the casing and having apertures that are large enough to permit the largest materials being treated to pass through the successive screens without lodging in the apertures, and means for producing currents of air passing upwardly through the inclined screens in opposition to the falling materials and of sufficient strength to pick up the finer 10 but not the coarser dust-like particles.
10. An air classifier for classifying fine-dust-like particles, comprising in combination, a casing, means for delivering the fine, dust-like materials to be treated into the upper portion of the casing to pass downwardly therein, a series of screens mounted in the casing in close proximity to each other and at a steep inclination to retard the downward passage of the materials 20 within the casing and to form narrow steeply inclined air passages between the adjacent screens, said screens being provided with apertures that are large enough to permit the largest particles being treated to pass through the successive screens without lodging in the apertures, and means for producing currents of air passing upwardly through the inclined screens in opposition to the falling materials and of sufficient 30 strength to carry off the finer but not the coarser dust-like particles.
11. An air classifier for classifying fine, dust-like particles, comprising in combination, a tower-like casing, several groups of deflector surfaces arranged within the casing in zigzag relation so that the materials being treated are directed alternately back and forth across the receptacle by the successive groups of deflectors, each of said 40 groups comprising a series of similarly inclined apertured surfaces through which the materials to be treated may pass in opposition to rising air currents, means for delivering the fine-dust-like materials to be treated to the upper part of the casing, and means for producing rising currents of air passing upwardly through the apertured surfaces in opposition to the falling materials to carry off the lighter particles.
12. An air classifier for classifying fine-dust-like particles, comprising in combination, a tower-like casing, several groups of screens mounted within the casing in zig-zag relation to direct the materials being treated alternately back and forth across the casing and each group consisting of a series of similarly inclined screens disposed in close relation to form narrow air passages between them, means for delivering the fine-dust-like materials to be treated to the upper part of the casing, and means for producing rising currents of air passing upwardly through the screens in opposition to the falling materials to carry off the lighter particles.
13. An air classifier for classifying fine-dust-like particles, comprising in combination, a casing, means for delivering the fine-dust-like materials to be treated into the upper part of the casing to pass downwardly therein under the influence of gravity, a plurality of oppositely inclined baffles mounted in the casing in zigzag relation to direct the materials back and forth across the casing, each baffle consisting of a group of similarly inclined deflector surfaces arranged to provide air passages between them, and means for producing currents of air passing upwardly between the deflector surfaces in opposition to the falling materials to carry off the lighter particles.

In testimony whereof, I have signed my name to this specification.

ALBERT H. STEBBINS.
